UNITED STATES PATENT OFFICE.

JOHN HARDEN BROOKS, OF FONDA, IOWA, ASSIGNOR OF ONE-FOURTH TO JOSEPH H. ALLEN AND ONE-FOURTH TO CHARLES D. ATKINSON, OF POCOHONTAS, IOWA.

COMBINED WRENCH AND PLIERS.

1,003,978.

Specification of Letters Patent. Patented Sept. 26, 1911.

Application filed August 16, 1909. Serial No. 513,088.

To all whom it may concern:

Be it known that I, JOHN H. BROOKS, a citizen of the United States, residing at Fonda, in the county of Pocahontas and State of Iowa, have invented a new and useful Combined Wrench and Pliers, of which the following is a specification.

The invention relates to a combined wrench and pliers.

10 The object of the present invention is to provide a simple, inexpensive and efficient tool, adapted for use either as a pair of pliers or a wrench, and capable of being quickly and easily adjusted to arrange it for 15 operating on the desired object.

20 A further object of the invention is to provide a tool of this character, equipped with jaws arranged substantially in parallelism when the members are closed, and 25 adapted to engage various objects, such as pipes, nuts, etc., with the square grip of a monkey wrench and without injuring the object or hurting the hand of the person using the tool.

25 With these and other objects in view, the invention consists in the construction and novel combination of parts hereinafter fully described, illustrated in the accompanying drawing, and pointed out in the claim 30 hereto appended; it being understood that various changes in the form, proportion, size and minor details of construction, within the scope of the claim, may be resorted to without departing from the spirit or 35 sacrificing any of the advantages of the invention.

In the drawing:—Figure 1 is a side elevation of a combined wrench and pliers, constructed in accordance with this invention. Fig. 2 is a longitudinal sectional view on the line 2—2 of Fig. 1. Fig. 3 is a longitudinal sectional view, taken at right angles to Fig. 2. Fig. 4 is a top plan view. Fig. 5 is a transverse sectional view, taken 45 substantially on the line 5—5 of Fig. 1.

Like numerals of reference designate corresponding parts in all the figures of the drawing.

50 The combined wrench and pliers comprises in its construction two members 1 and 2, having inner handle portions and provided with outer laterally extending jaws 3 and 4, arranged substantially at right angles to the bars or members 1 and 2. The jaws 55 3 and 4 are provided with outer smooth

portions 5, and have inner transverse corrugations or teeth 6, whereby the jaws are adapted to firmly grip and securely hold any object, which may be placed between the jaws. Also the jaws by being arranged 60 at substantially right angles to the bars or members are disposed in parallelism when the handle portions of the said bars or members are at the limit of their relative inward movement, whereby the jaws are 65 adapted to grip a nut or other object with the square grip of a monkey wrench. The bar or member 1 is provided at an intermediate point with a bend, which spaces the handle portions of the levers from each 70 other when the jaws are closed.

The bar or member 2 is provided adjacent to its jaw 4 with a longitudinal opening 7, forming spaced side walls and a rear connecting wall, as clearly illustrated in 75 Fig. 5 of the drawing. The other member 1 extends through the opening 7 and is provided adjacent to its jaw 3 with a longitudinal groove and having a longitudinal series of bearing sockets 8, arranged at intervals at the bottom of the groove and adapted 80 to receive a pivot or stud 9 of a lever 10, whereby the two members are pivotally connected and are adapted to be oscillated to open and close the jaws 3 and 4. The series 85 of bearing sockets 8 provide for a relative longitudinal adjustment of the members to vary the distance between the jaws, and as the distance between the jaws increases, the length of the tool correspondingly increases, 90 thereby increasing the leverage or power of the tool. The lever 10 is arranged on the exterior of one of the side walls of the opening 7 and is provided at a point between its ends with an ear 11, extending into a slot 95 12 of the adjacent side wall and pivoted to the same by a transverse pin 13, which pierces the ear and also spaced lugs or enlargements 14 of the bar or member 2. The stud 9 is carried by the upper or outer end 100 of the lever and is maintained in engagement with the bar or member 1 by a coiled spring 15, seated against the inner face of one of the side walls of the longitudinal opening 7 and extending through an opening 16 of the other side wall and bearing against the inner face of the adjacent lever 10. The inner end of the lever and the side wall against which the spring bears are equipped with projections 17 and 18, which 110

extend into the ends of the coiled spring and maintain the same in position. The tool may be instantly and quickly adjusted by depressing the inner end of the lever and 5 sliding the bars or members longitudinally of each other to arrange the jaws the desired distance apart. The bars or members are provided with wire-receiving notches 19 and 20, forming a wire cutter when the bar or 10 member 1 is at the inward limit of its relative longitudinal adjustment, and the stud or pivot 9 is seated in the bearing socket at the outer end of the series, as illustrated in Fig. 1 of the drawing. The wire to be 15 severed is placed in the notches when the same are in register, and the members are then operated to carry the notches away from each other, which cuts the wire in the usual manner.

20 It will be observed that the pivot may be adjusted to space the jaws from each other to accommodate nuts of different sizes, and when the pivot is adjusted in the bearing socket nearest the jaws, the handles may be 25 swung on the pivot to bring the straight outer faces of the jaws in contact. In this position, the tool may be operated as a pair of pliers.

Having thus fully described my invention, what I claim as new and desire to secure by Letters Patent, is:—

A tool of the class described including two members, each provided at one end with a handle and at the other end with a jaw, one of the members being also formed adjacent 35 to its jaw with a longitudinal opening to receive the other member and the latter having a plurality of perforations adjacent to its jaw, a lever fulcrumed between its ends on the exterior of the member having the longitudinal opening and provided at its outer end with a pivot piercing the adjacent side 40 wall of the said opening and engaging with one of the bearings, and a spring seated against the inner face of the opposite side 45 wall of the said opening and extending across the latter and through the opposite wall thereof and bearing against the inner end of the lever.

In testimony, that I claim the foregoing as my own, I have hereto affixed my signature in the presence of two witnesses.

JOHN HARDEN BROOKS.
